UNITED STATES PATENT OFFICE.

HARVEY C. GILES, OF ROCHESTER, NEW YORK.

RIVETING-MACHINE.

1,394,506.

Specification of Letters Patent. Patented Oct. 18, 1921.

Application filed June 21, 1920. Serial No. 390,560.

To all whom it may concern:

Be it known that I, HARVEY C. GILES, citizen of the United States of America, residing at Rochester, in the county of Monroe 5 and State of New York, have invented certain new and useful Improvements in Riveting-Machines, of which the following is a full, clear, and exact specification.

This invention relates to riveting machines, and more particularly to machines for light riveting work for joining thin sheets of material and has for its object to provide a machine which will strike the work each time with a uniform blow; another object is to provide a machine using a trip hammer for striking the rivet, means being provided for adjusting the weight of the blow; still another object is to provide a machine which can easily be operated manually; a further object is to provide a machine in which a pad descends upon and holds the work in place before the hammer is operated; and a still further object is to provide a machine which can be used by an unskilled operator successively; and other objects will hereinafter appear.

In the accompanying drawings, in which like reference characters designate like parts:

30 Figure 1 is a section through a machine constructed in accordance with, and illustrating one embodiment of my invention, parts being shown in elevation;

Fig. 2 is a plan view of the machine shown in Fig. 1;

Fig. 3 is a side elevation of the same machine, the hammer being raised to strike a blow;

Fig. 4 is a fragmentary section of a work pad which may be used with my machine; and

Fig. 5 is a detail section through one type of hammer weight, taken on line 5-5 of Fig. 3.

45 In the embodiment of my invention shown, a base 1 carries a standard 2, from which an arm 3 extends forwardly over the base. The arm 3 is apertured through the central portion 4, and terminates in a cylindrical bearing 5. The top of the standard 2 is forked, the sides 6 and 7 forming bearings 8 and 9 for two levers. The top lever 10 serves as a hammer, and the lower lever 11 is for setting and tripping the hammer and

50 55 for moving the work-holding pad.

To actuate the hammer lever 10, there is

a latch 12, pressed against a stop 13, by a spring 14, the latch being pivoted to lever 10 by a pin 15. These parts all fit into a recess 16 cut into the side of lever 10. The latch 12 contacts with a cam lug 17 which here is shown as being formed of a metal disk 18 which is fastened to lever 11 by pins 19. Lever 11 is in the form of a yoke having an extended arm 20 on one end which supports one end of a spring 21 upon a hook 22. The other end of spring 21 is fastened to base 1 by an eyelet 21'. The arms 23 and 24 of lever 11 contain elongated bearings 25 and 26 which slide about stub shafts 27 and 28 carried by ears 30 and 31 of a tubular sliding member 29. This construction provides a clear space or opening through which the hammer may strike the plunger 32 which slides through a bearing 33 in the top of the cylinder 29. There is a head 34 on the lower end of plunger 32 which slides in cylinder 50 with a loose fit, so that air is not compressed by its movement. Air vents may be made in head 34, if desired, but I have not found this necessary, the loose fit being cheaper to make and satisfactory in operation.

Arms 23 and 24 of lever 11 are connected by a bridge 35 carrying on its under side an eyelet 36 to which a cable 37 is attached, the other end of the cable being fastened to a foot treadle, not shown. Just behind bridge 35 there is a base 38 in which a spring terminal 39 is fastened, a nut 40 permitting the adjusting of a spring 41 attached to levers 10 and 11. A pin 42 holds one end of a spring 41 in the slot 43 of lever 10. As cable 37 is drawn down lever 11 will cause the sliding cylinder 29 to move toward base 1, while at the same time latch 12 is rotated through cam lug 17 until the hammer reaches the position shown in Fig. 3. In this position the work pad 44 is in contact with the work 45, holding it in position. By continuing the downward movement of lever 11 the latch 12 rides over the top of the cam lug or dog 17, so that it drops, the weight of the lever and tension of the spring determining the blow.

The speed with which the foot treadle is operated can not affect the stroke of the hammer, so that each time a uniform blow is delivered. If a heavier blow is desired, the spring 41 may be put under greater tension, but generally I prefer to alter the weight of, or change the leverage of, the hammer weight. In Fig. 1, this is accom-

plished by means of inserting a weight plug 46 in an aperture 47 drilled in arm 10. A series of the weights and apertures may be provided so that, either the same weight 5 may be placed in positions along arm 10 at different mechanical advantage points relative to the lever 10, or plugs of different weights may be used, or any desirable combination of both. In Figs. 3 and 5, the blow 10 of the hammer is adjusted by moving the weighted slide 48 along lever 10 fastening it in the desired position by a set screw 49.

The work holding pad 44 is constructed of a tubular member 50 slidable in member 29, 15 which in turn slides in bearing 5 supported from the base. The sliding movement of member 29 relative to bearing 5 is limited by a pin 51 in the bearing extending into a slot 52 in member 29. There is also a pin 53 20 carried by member 29 which limits the movement of member 50 through the slot 54 in member 50. A coiled spring 55 tends to keep member 50 toward the base 1. The bottom of member 50 is threaded at 56 to take 25 a work-holding pad 44, shown in Fig. 1 as being provided with a tool guideway 57, and a reduced work contacting face 58. The tool 75 is mounted on a disk 59 loosely sliding in member 50, in such a position that the 30 disk 59 is struck by the plunger when the hammer descends. In Fig. 1 the disk 59 and tool 75 are shown resting against the head 34 on the end of plunger 32 because this is the position of these parts before the tool is 35 operated. It should be noted, however, that normally when the work holder is raised, the tool 75 will be extending down from the holder as shown in dotted lines. When lever 11 lowers pad 44 the tool 75 will strike first, 40 and, having no pressure upon disk 59, will move to the position shown in full lines, from which position it is struck by the hammer mechanism. This movement of tool 75 is useful, because, in some classes of work it 45 assists in placing the work properly, acting as a centering tool. Any desired number of tools can be carried by providing a special disk 59 and holding pad 44, in Fig. 4 a twin riveting tool being shown, the disk 59 carrying tools 60 and 61, while the work holder 50 has twin guideways 62 and 63, and holding pads 64 and 65. Various tools can be readily adjusted, by merely screwing on an end 44, suited to the particular job, to the member 55 50.

The work 45, is carried upon a table 68 which is provided with a downwardly extending stem 69 which frictionally engages in a slot 70 in base 1. In the form illustrated 60 the aperture 70 is circular in cross section, although sometimes it is desirable to make it so that the table stem 69 can not turn in the aperture, so that a square or other shaped opening can be advantageously used.

65 The operation of my machine is as fol-

lows: An operator selects a disk 59 with a tool 75 suited to his work, and, after placing these in cylinder 50, screws on pad 44. The desired weight 46 is then placed on the hammer and the machine is ready for use. The work 45 is then placed upon table 68, and the foot lever depressed pulling down on cable 37 thereby causing lever 11 to revolve on its pivot 9. The work pad 44 descends at the same time hammer 10 is ascending from 75 the table, hammer 10 being actuated through latch 12 and dog 17. When the pad 44 reaches the work 45 spring 55 is slightly compressed by further downward movement of lever 11, so that the work is held firmly 80 in position. Continuing the movement of the foot treadle the parts reach the position shown in Fig. 3, at which point latch 12 rides over the cam 17, causing the hammer to sharply strike the plunger 32, which, 85 through head 34, strikes disk 59, thereby delivering a blow upon tool 75. This cycle of operations can be very rapidly performed, a uniform blow being struck regardless of the speed of actuation of the machine. 90

Usually it is customary to have a work centering device on table 68, but where special work is being done, lever 11 can be slowly depressed so that the work can be adjusted over table 68 manually and centered 95 by tool 75, which, upon further depressing of lever 11, will be moved up into the position from which it is struck, shown in Fig. 1.

I do not wish to limit myself to the machine illustrated since it will be obvious to those skilled in the art that certain changes can be made without departing from the spirit of my invention. For instance, the device can be readily operated manually by hand instead of by foot as described, or if 105 desirable, it may be run by power, a suitable clutch being interposed between the source of power and the actuating lever 11.

Having thus described my invention what I claim as new and desire to secure by 110 Letters Patent is:

1. In a riveting machine, the combination with a reciprocating work-holding pad, of a riveting tool confined to a predetermined path by the pad, a lever for reciprocating 115 the work-holding pad, and a hammer for striking the riveting tool, the lever actuating the hammer.

2. In a riveting machine, the combination with a reciprocating pad, of a plunger carried by the pad, a lever for reciprocating the pad, and a hammer for striking the plunger, means carried by the lever for setting the hammer to strike. 120

3. In a riveting machine, the combination 125 with a reciprocating pad, of a plunger carried by the pad, a lever for reciprocating the pad, and a hammer for striking the plunger, means carried by the lever for setting and then tripping the hammer. 130

4. In a trip hammer for riveting work, the combination with a tool mounted in a tool holder, of a lever for positioning the tool with respect to the work, and a hammer having an operative and an inoperative position, the lever causing the hammer to rotate away from the work into an operative position from which it will drop to strike the tool. 5. In a trip hammer for riveting work, the combination with a tool mounted in a tool holder, of a lever for positioning the tool with respect to the work, and a hammer having an operative and an inoperative position, the lever causing the hammer to rotate away from the work into an operative position from which it will drop to strike the tool, and means on the lever for tripping the hammer. 10. 6. In a trip hammer for riveting machines, the combination with a tool mounted to reciprocate above the work, of a base, a lever and a hammer both pivoted to the base, means for applying power to one of the pivoted members so that the hammer and the lever will first rotate in opposite directions about their pivots and then rotate in the same direction, thereby causing the hammer to strike the tool. 15. 7. In a trip hammer for riveting machines, the combination with a riveting tool, of a hammer for actuating the tool, a base carrying the hammer, and a lever pivoted to the base, means for moving the hammer from the base as the tool is positioned, and means for tripping the hammer after the tool is positioned. 20. 8. In a trip hammer for riveting machines, the combination with a base, of a riveting tool slidably mounted above the base, a lever and a hammer both pivoted to the base, a connection between the lever and hammer tending to hold them together and a connection between the lever and hammer by which they will be rotated apart when power is applied to one of them, said last mentioned connection being adapted to automatically release the hammer so that it may move toward the lever to strike the tool. 25. 9. In a trip hammer for riveting machines, the combination with a base, of a tool movably mounted above the base, a lever and a hammer pivoted to the base, one carrying a latch and the other a dog, means for raising the hammer through the latch and dog and means for tripping the hammer at a predetermined elevation, whereby the hammer will strike the tool. 30. 10. In a riveting machine, the combination with a riveting tool, of a work holding pad mounted to reciprocate above the work, a lever for moving the pad, the work holding pad comprising three telescoping cylinders, two movable with respect to the third, means tending to hold the movable cylinders apart, and means for limiting the movement of all of the cylinders relative to each other, the lever moving the cylinders to hold the work in position, and means for striking the riveting tool. 35. 11. In a riveting machine, the combination with a base, of a riveting tool movably supported by the base, a lever for moving the riveting tool toward work carried by the base, a spring for normally holding the lever in one position, and a hammer mounted on the base, a spring connecting the lever and the hammer, means for moving the lever to carry the riveting tool toward the base, said movement placing the springs under tension. 40. 12. In a riveting machine, the combination with a base, a riveting tool mounted to move over the base, of a lever having an operative and an inoperative position, a spring for normally holding the lever in its inoperative position, a hammer carried by the base movable into and out of an operative position, and a spring for normally holding the hammer out of operative position, and means for moving the lever to bring the riveting tool toward the base, thereby putting both springs under tension, so that when the lever moving means is released the parts will return to their inoperative positions. 45. 13. In a riveting machine the combination with a base, of a bearing supported by the base, a sliding work pad carried in the bearing, a tool slidably carried by the work pad, and a lever for moving the said pad and tool toward and from the base, a hammer carried by the base and movable to and from a striking position, and means for varying the force of the blow struck by the hammer in descending from its striking position upon the tool. 50. 14. In a trip hammer for riveting machines, the combination with a base, of a hammer, adapted to move up and down with respect to the base, a pivot connecting the hammer to the base, a riveting tool slidably carried by the base, means for moving the riveting tool toward the base comprising a lever pivoted to the base, said lever in lowering the riveting tool toward the base imparting an up and down movement to the hammer. 55. 15. In a trip hammer for riveting machines, the combination with a base, having a work table thereon, of a hammer carried by the base and movable to and from the work table, a riveting tool slidably mounted above the work table, and means for lowering the riveting tool to the work on the table, said means also raising the hammer so that it will drop by gravity to strike the riveting tool. 60. 16. In a trip hammer for riveting ma-

chines, the combination with a base, having a work table thereon, of a hammer carried by the base and movable to and from the work table, a riveting tool slidably mounted above the work table, and means for lowering the riveting tool to the work on the table, said means also raising the hammer so that it will drop by gravity to strike the riveting tool, and means carried by the hammer for varying the force of the blow.

17. In a trip hammer for riveting machines, the combination with a base, having a work table thereon, of a riveting tool mounted on the base movable to and from the work table, a hammer pivoted to the base for striking the riveting tool, and a lever for moving said riveting tool, the downward movement of the lever raising the hammer and releasing it to strike the riveting tool, and means for controlling the force of the blow delivered by the hammer by varying the weight thereof.

18. In a trip hammer for riveting machines, the combination with a base, having a work table thereon, of a riveting tool mounted on the base movable to and from the work table, a hammer pivoted to the

base for striking the riveting tool, and a lever for moving said riveting tool, an adjustable spring connecting the hammer and the lever, the movement of the lever in positioning the riveting tool raising the hammer and releasing it to strike the riveting tool, the adjustment of the spring permitting the force of the blow to be varied.

19. In a trip hammer for riveting machines the combination with a base, carrying a work table, of a riveting tool mounted to slide to and from the work table, a hammer pivoted to the base so as to move to and from the riveting tool for striking the riveting tool, and a lever for positioning the work tool, said lever moving the hammer and the riveting tool away from each other during the first part of the positioning of the riveting tool and then releasing the hammer to strike the riveting tool, there being means for adjusting the force of the blow struck by the hammer comprising an adjustable weight and an adjustable spring.

Signed at Rochester, New York, this 16th day of June, 1920.

HARVEY C. GILES.
